Primary Examiner—Prabhakar Deshmukh(74) *Attorney, Agent, or Firm*—Wallenstein Wagner & Rockey, Ltd.**CLAIM**

I claim the ornamental design for a tilt-latch, as shown and described.

DESCRIPTION

FIG. 1 is a perspective view of a tilt-latch showing my new design;

FIG. 2 is a top plan view thereof;

FIG. 3 is a side elevational view thereof, the opposite side elevational view being identical;

FIG. 4 is a front elevational view thereof; and,

FIG. 5 is a rear elevational view thereof.

The undisclosed bottom portion is plain and unornamented and the broken lines are for illustrative purpose only and form no part of the claimed design.
